UNITED STATES PATENT OFFICE.

KONRAD JAGSCHITZ, OF MAINZ, GERMANY, ASSIGNEE TO MASCHINENFABRIK AUGSBURG-NÜRNBERG, A. G., OF NUREMBERG, GERMANY, A CORPORATION OF GERMANY.

COLLECTING MEANS FOR THE SEALING LIQUID OF DRY GASOMETERS.

Application filed November 14, 1924. Serial No. 749,848.

To all whom it may concern:

Be it known that I, KONRAD JAGSCHITZ, a citizen of Germany, and resident of Mainz, Germany, have invented certain new and useful Improvements in Collecting Means for the Sealing Liquid of Dry Gasometers, of which the following is a specification.

My invention relates to gasometers of the type shown for instance in United States Patent No. 1,275,696 and which include a vertically movable sealing disc and are commonly referred to as dry gasometers. In such gasometers, a sealing liquid is caused to trickle over the inner surface of the gas container and constitutes the medium whereby the joint between the sealing disc and the container is sealed. The object of the present invention is to provide a novel and efficient means for collecting the sealing liquid and for maintaining an undisturbed flow of such liquid. The invention contemplates further the provision of a construction whereby the amount of the flowing liquid may be adjusted to supply the liquid to the seal in the most desirable and efficient quantity. Other objects will appear from the description hereinafter and the features of novelty will be pointed out in the claims.

In the accompanying drawing, which illustrates an example of the invention without defining its limits, Fig. 1 is a fragmentary vertical section; Fig. 2 is a similar horizontal section on the line 2-2 of Fig. 1 and Fig. 3 is a detail view in vertical section illustrating another form of a controlling element forming part of the invention.

As shown in the drawings, the invention comprises a container or gasholder 10 which may be of the form shown in the above mentioned patent and includes a vertically moving sealing disc 11 constructed in any well known way for reciprocation vertically along the inner surface of the container 10 in accordance with the quantity of gas contained therein; a trough or its equivalent 12 extends peripherally of the sealing disc 11 in contiguous relation to the inner surface of the container 10 and receives the liquid 13 whereby the joint between said sealing disc and the container 10 is sealed. The sealing liquid 13 is caused to trickle over the inner surface of the container 10 from re-

ceptacles usually located at the upper portion of the tank and is temporarily held in the trough 12 in sufficient quantity to effect a gas-tight seal between the sealing disc 11 and the container 10; after having performed its functions in the trough 12, the sealing liquid trickles downwardly therefrom into the annular channel 14 located upon the bottom of the container 10, as shown in Fig. 1. As so far described the construction may be of any well known type and may include such features as are commonly found in gasometers of the character under discussion.

The present arrangement includes a collecting tank comprising a shell 15 of metal or other suitable material sunk into the ground at a point outside of the container 10, for instance as indicated in Fig. 1. A dip pipe 16 closed at its upper end and open at its lower end extends into the tank 15 so as to terminate at a distance from its bottom and to project for a considerable distance into the sealing liquid 13 which is collected in said tank, as will appear more fully hereinafter. The dip pipe 16 which is of relatively large diameter is preferably located near one end of the tank 15, the latter, as shown in Fig. 2, being of generally rectangular form; a horizontal connecting pipe 17 extends from the upper portion of the dip pipe 16 to the container 10 near the bottom thereof and serves to connect the latter with the dip pipe as shown in Fig. 1. In the preferred arrangement, the connecting pipe 17 is of such length and is yieldingly attached to both the container 10 and the dip pipe 16 in such a manner that a foundation settlement will not interfere with the safe and proper operation of the collecting tank.

This pipe 17 serves to conduct the sealing liquid 13 which is collected in the annular channel 14 to the dip pipe 16 and thence to the tank 15. The sealing liquid generally speaking consists of tar or a similar product, the flow of which to the collecting tank 15 should be capable of adjustment to provide the best results. For this purpose, an adjustable weir 18 may be located in the connecting pipe 17 so as to be pivotally adjustable therein by means of an exteriorly located handle 19 or its equivalent. In addition, a gate valve or its equivalent 20 may

be provided in the connecting pipe 17 for completely disconnecting the dip pipe 16 from the container 10.

At the end which is opposite to that end

- 5 at which the dip pipe 16 is located, the tank 15 is provided with a pipe 21 which serves to connect said tank with a suitable pump whereby the sealing liquid is conveyed from the tank 15 to the collecting means or tanks
- 10 located generally in the upper end of the container 10; as the latter are well known in the art and form no part of the present invention, it has not been deemed necessary to illustrate the same. In order that the
- 15 pump may be automatically controlled in such a manner as to operate only when the sealing liquid collected in the tank 15 reaches a predetermined level, a float 22 is provided which rises and falls with the
- 20 changes in the level of the liquid 13 in the tank. The float 22 is connected by means of a rod 23 with a lever 24 which in turn operates a connection 25, whereby the starting and stopping of the aforesaid pump is
- 25 controlled. As such arrangements are well known, it is not considered necessary to either illustrate or describe the same further.

- 30 In order to prevent foreign objects or matter which might float on top of the sealing liquid from interfering with the float 22 and to prevent water which might pass in small amounts from the dip pipe 16 to the tank 15 and form ice during freezing
- 35 weather from similarly interfering with said float 22, the partition 26 is provided in the tank 15. This partition divides the tank 15 into two independent chambers *a* and *b* which communicate with each other by
- 40 way of the bottom of said partition, the latter being spaced from the bottom of the collecting tank 15 as shown; the liquid 13 is thus forced to pass from the chamber *a* of the tank 15 to the chamber *b* beneath the partition 26. Any foreign matter, water or
- 45 the like, which may float upon the surface of the liquid in the main portion of the tank will therefore simply rise and fall with changes in the level of said liquid and accordingly will not reach the chamber *b*; any
- 50 ice which may form as a result of the presence of such water will thus be maintained out of contact with the float 22. A second partition 27 may be provided upon the bottom of the tank 15 at a distance from the partition 26 as shown in Fig. 1. This second partition extends far enough above the lower end of the dip pipe 16 to provide an adequate liquid seal therefor at all times in the chamber *a* so that even if the liquid level in the chamber *b* of the tank descends to said lower end of the pipe, the gas in the holder will still be sealed against escape by way of the tank 15. The upper edge of the partition 27 furthermore should be so ar-

ranged as to permit a proper flow of liquid between the chambers *a* and *b* and accordingly between the dip pipe 16 and the suction pipe 21.

In operation, the sealing liquid 13 passes 70 from the annular channel 14 through the pipe 17 and the dip pipe 16 into the tank 15. As the level of said liquid rises and falls in the tank 15, the float 22 will rise and fall accordingly and thereby will start and stop 75 the pump to automatically transfer the liquid 13 from the tank 15 to the collecting tanks or their equivalent at the upper end of the receptacle 10. The flow of the liquid from the channel 14 through the pipe 17 80 may be adjusted by setting the weir 18 in different positions, as will be apparent from an inspection of Fig. 1 of the drawings. If it is desired to completely disconnect the receptacle 10 from the tank 15, the gate valve 85 20 or its equivalent may be operated accordingly. Because of the fact that the gas pressure in the receptacle 10 is effective in the dip pipe 16, the level of the liquid is lower than the level of said liquid in the 90 tank 15 as indicated, for instance, in Fig. 1. At the point at which the level of the liquid in the dip pipe 16 is located, a drain connection 28 is provided for drawing off such water as may float upon the top of the sealing liquid in said dip pipe 16; the latter is made of large diameter, so that the withdrawal of this water is facilitated.

In place of the two independent elements 18 and 20 for controlling the flow of sealing liquid and the connection between the container 10 and the dip pipe 16, a single element constructed and arranged to perform the functions of said two independent elements may be substituted. As shown in 100 Fig. 3 said single element may consist of a gate valve 20^a, the valve member 20^b of which, contrary to the normal operation thereof, is arranged to be operatively shifted from a lowermost open position to an uppermost closed position. By setting the member 20^b to intermediate positions, for instance, as indicated in Fig. 3, the upper edge thereof serves as a weir which may be adjusted to any desired level to control the flow of the sealing liquid to the tank 15; the valve member 20^b, when in its fully raised position, completely closes the connection between the container 10 and the dip pipe 16.

The arrangements set forth and described 120 efficiently maintain an undisturbed flow of the liquid between the gasholder where the liquid is first collected and the outside collecting tank, which is essential to the efficient operation of gasholders of the indicated type. At the same time, the amount of the flowing liquid can be adjusted so as to supply the liquid in the desired amount to any of the outside collecting tanks. The construction furthermore provides an effi- 130

cient arrangement whereby escape of gas is prevented in case the collecting tank should be pumped dry. In addition to this, the flexible connections of the pipe 17 with the 5 container 10 and the tank 15 are such that in case of settlement of the gas holder foundation the joints between the connecting pipe and said container and tank will remain undisturbed. Furthermore the collecting tanks and their attachments may be 10 readily shut off or disconnected from the gasholder to permit repairs and the like and in addition interfere with the proper operation of the floats whereby the pumps are controlled is positively prevented at all 15 times, including freezing weather.

Various changes in the specific form shown and described may be made within the scope of the claims without departing 20 from the spirit of my invention.

I claim:

1. The combination of a gas holder having a vertically movable sealing disc arranged to be sealed by a sealing liquid, a 25 collecting tank for the said sealing liquid from which the latter is circulated by means of a pump, a dip pipe of large diameter, the lower open end of which dips below the level of the liquid that collects in said tank 30 and which is closed at its upper end, a horizontal pipe connecting the upper end of said dip pipe with the gas holder near its bottom for conducting the sealing liquid from the gas holder to the collecting tank, a gate 35 valve in the horizontal connecting pipe, an adjustable overflow for adjusting the flow of the sealing liquid from the gas holder to the collecting tank, a float located inside of the said collecting tank, attachments 40 connected with the float whereby the circu-

lation of the liquid by the pump is controlled, a partition separating the liquid around the float from the rest of the liquid in the collecting tank and a second partition mounted upon the bottom of the tank and 45 extending above the lower end of the dip pipe.

2. The combination of a gas holder having a vertically movable sealing disc arranged to be sealed by a sealing liquid, a 50 collecting tank for said sealing liquid from which the latter is circulated by means of a pump, a dip pipe of large diameter, the lower open end of which dips below the level of the liquid that collects in said tank and 55 which is closed at its upper end, a horizontal pipe connecting the upper end of said dip pipe with the gas holder near its bottom for conducting the sealing liquid from the gas holder to the collecting tank, a gate 60 valve in the horizontal connecting pipe, including a valve member adjustable from a lowermost open position to an uppermost closed position when the pipe is to be shut off, and arranged when only partly shut to 65 serve as an adjustable weir for adjusting the flow of the sealing liquid from the gas holder to the collecting tank, a float located inside of the said collecting tank, attachments 70 connected with the float whereby the circulation of the liquid by the pump is controlled, a partition separating the liquid around the float from the rest of the liquid in the collecting tank and a second partition 75 mounted upon the bottom of the tank and extending above the lower end of the dip pipe.

In testimony whereof I have hereunto set my hand.

KONRAD JAGSCHITZ.
